MESNE ASSIGNMENTS, TO THE LAWRENCE MANUFACTURING COMPANY LIMITED,
OF LONDON, ENGLAND.

TYPE-WRITER.

1,111,868.

Specification of Letters Patent. Patented Sept. 29, 1914.

Application filed May 9, 1911. Serial No. 625,981.

To all whom it may concern:

Be it known that we, ZALMON G. SHOLES and JOSEPH M. FRAAZ, citizens of the United States, residing in the city, county, and State of New York, have invented new and useful Improvements in Type-Writers, of which the following is a specification.

This invention has relation to the means for holding and controlling a paper which is being written upon in the typewriter and more particularly to means whereby the platen can be connected with and disconnected from the line spacing mechanism.

The invention is illustrated in preferred form in the accompanying drawings, where-

Figure 1 is a front elevation of the entire device. Fig. 2 is a plan view thereof. Fig. 3 is a sectional view taken on the line 3—3 in Fig. 2. Fig. 4 is a sectional view taken on the same line looking in the opposite direction. Fig. 5 is an elevation of the pawl sector. Fig. 6 is an elevation of a portion of the spacing mechanism partly broken away. Fig. 7 is a face view of the ratchet-disk. Fig. 8 is a sectional view taken on the line 8—8 in Fig. 4. Fig. 9 is a face view of the releasing sector, and Fig. 10 is a sectional detail view of the ratchet release.

The platen is shown at 10 and is mounted upon the usual platen shaft 11 furnished at its two ends with a cylindrical portion 12—13 to permit the turning of the platen directly by hand. The platen is fixed to the shaft 11 by any desired means and in the form shown, by the set-screw 14. One end of the platen 10 is mounted upon the hollow hub 15 of a spacing ratchet 16 which, in turn, is mounted upon the sleeve 17, turning loosely on the shaft 11. Said sleeve 17 is preferably fastened to the ratchet by means of the screw 18. Turning freely on the sleeve 17 and placed flat upon the face of the spacing ratchet 16 is mounted the releasing sector 19 which is provided with a handle 20, with teeth 21, and with a releasing projection 22. (See Fig. 6). Fitted over the face of the sector 19 is the pawl-carrying sector 23 which is provided with the teeth 24 and the pawl 25, which pawl is normally held in contact with the teeth on the ratchet by means of the spring 26, preferably acting upon the tail of the pawl back of the pivot

27 upon which the pawl is mounted. (See Fig. 4).

It will be seen that by pushing the handle 20 in the direction of the arrow in Fig. 4, the sector 19 will be so turned that its releasing projection 22 will push the pawl 25 out of engagement with the ratchet 16 and thus free the platen from the line spacing mechanism which normally acts as follows: Upon an upright shaft 28 adjacent to the end of the platen is mounted a bell-crank lever 29, one branch of which is composed of a toothed-sector 30 which normally engages with the teeth 24 on the sector 23 and it is obvious that by pushing the outer handle 29 to the right in Figs. 1 and 2, the sector 30 acts to revolve the sector 23 and to turn the platen by means of the pawl 25 and ratchet 16. The return movement of the lever 29 is accomplished by a spring 31 which is preferably a spiral spring mounted below the lever 29 within the housing 32 and surrounding the shaft 28. This return movement has, of course, no action on the platen as the pawl 25 merely slips idly backward over the teeth of the ratchet 16. The sector 19 is capable of assuming three positions which are indicated by the numbers 1, 2 and 3 on the left of Fig. 1 and which positions are ascertained and preserved by the engagement of the teeth 21 with the extremity 33 of the spring 34 mounted on the carriage adjacent to the end of the platen.

When the handle 20 is raised opposite the number 1 the pawl 25 is thrown into the dotted line position shown at 35, in Fig. 6, and the platen is free. In the position marked 2, the projection 22 on the sector 19 is in the position shown in Fig. 6, and the pawl 25 is active only during movement through the distance of one tooth of the ratchet 16. If double line spacing is required on the paper, the handle 20 is placed in the position marked 3 in Fig. 1 when the projection 22 is withdrawn far enough so that the pawl 25 is active through the space of two teeth.

The normal line spacing is ascertained and preserved steady by means of the roller 36 mounted on the spring 37 which normally presses against the teeth of the ratchet 16 and lies between them. The extremity of the spring 37 bears upon a shaft 38 which is

half cut away in Fig. 10 and also as shown in Fig. 3, so that in one position of the shaft, the spring will be pushed to the left as shown in Fig. 8 thus withdrawing the roller 5 from the ratchet teeth and in the other position, the spring will fall against the flat face of the cut away portion 49 and occupy the dotted line position shown in Fig. 10, thus allowing the roller to fall between the teeth 10 of the ratchet. The shaft 38 is turned by means of the external lever 39 and thus the platen is freed from the roller 36 to permit of fractional movements between normal line spacing.

15 The paper is normally clamped against the platen by means of resilient rollers 40 turning upon longitudinal shafts 41 mounted on the extremities of arms 42 which arms are pivoted below on a common shaft 43.

20 Said arms are shaped as shown in Fig. 3 with substantially upright portions which rest upon opposite sides of a bar 44 which is flat or otherwise shaped to carry out the function had in view, and the arms 42 are 25 held against the bar 44 by means of springs 45 surrounding said bar at intervals as shown in Figs. 1, 2 and 8. In the form 30 shown, the bar 44 is flattened only where it makes contact with the arms 42 but a variety 35 of forms can be given to this bar without departing from the invention. The bar 44 can be revolved in end bearings 46 and 47 by means of the handle 48 and it is obvious that 40 when turned through an angle of 90 degrees 45 with respect to the position shown in Fig. 3, the flat portion of the bar 44 will act to push the arms 42 apart and thus release the paper from the platen. This 90 degree position 50 will be preserved by the pressure of the 40 springs 45 and the action of the flat surfaces of the arms 42 against the edges of the flat part of the bar 44.

The means above described for pressing the paper against the underside of the platen 45 are not herein claimed as they will form the subject matter of a divisional application.

The construction thus described affords a very simple and reliable mechanism for carrying out the ends had in view and one 50 involving comparatively few parts.

Our invention may be carried out by mak-

Washington, D. C."**

ing various modifications in this device, and we do not limit ourselves to the details herein shown and described.

What we claim is—

1. In a typewriter, a platen, a ratchet wheel thereon, a roller, a spring mounting for said roller for normally pressing the same between the teeth of said ratchet, and a revoluble shaft having a flattened portion bearing against said spring for controlling said roller, substantially as described. 55

2. In a typewriter a platen provided with a ratchet 16 having teeth projecting horizontally from one end thereof, a releasing sector rotatably mounted concentrically with said platen just in front of said teeth and having a releasing projection, a pawl-carrying sector having a pivoted spring-pressed pawl adapted to engage with said teeth and placed in the path of movement of said releasing projection, said sector being mounted concentrically with said platen just outside of said releasing sector, substantially as described. 60

3. In a typewriter, a platen having a spacing ratchet with horizontally projecting teeth, a releasing sector placed flat against said spacing ratchet and a pawl carrying sector rotatably mounted outside of said releasing sector and parallel to it and said ratchet, said pawl bearing sector having an external circumferential flange extending over and protecting said releasing sector and the teeth of said ratchet, substantially as described. 70

4. In a typewriter a platen having a spacing ratchet with horizontal projecting teeth, a releasing sector placed flat against the said spacing ratchet, and a pawl-carrying sector 75 rotatably mounted concentrically with said releasing sector, and one of said sectors having an external circumferential flange, extending over and protecting the other sector and the teeth of said ratchet, substantially as described. 80
